Primary Examiner—Lucy Lieberman

(57) **CLAIM**

The ornamental design for a face for a timepiece, as shown and described.

DESCRIPTION

FIG. 1 is a front elevational view of a face for a timepiece showing my new design;

FIG. 2 is a front elevational view showing a modified form of my new design;

FIG. 3 is a front elevational view showing another modified form of my new design; and,

FIG. 4 is a front elevational view showing still another modified form of my new design.

The front of the face for a timepiece is flat and solid.
